UNITED STATES PATENT OFFICE.

MAJOR E. GATES, OF TERRA COTTA, ILLINOIS.

ART OF PRODUCING ORNAMENTAL SURFACES.

1,427,454.

Specification of Letters Patent. Patented Aug. 29, 1922.

Application filed April 28, 1920. Serial No. 377,341.

To all whom it may concern:

Be it known that I, MAJOR E. GATES, a citizen of the United States, residing at Terra Cotta, in the county of McHenry and State of Illinois, have invented a new and useful Improvement in the Art of Producing Ornamental Surfaces, of which the following is a specification.

My invention relates, more particularly, to the production of speckled or mottled surfacings, produced by the application of coating material of a plurality of colors, more particularly, though not exclusively, to surfacings of building structures, as for example walls of such structures, or the blocks, or the like, of which the building structure is formed, as for example terra cotta blocks; and my primary object is to produce the desired ornamental effect in the use of multicolor surface coatings and of the character stated, and by a simple and economical operation.

As a premise to the following description it may be stated that the invention as to one phase thereof, contemplates discharging, against a surface to be coated, of differently colored fluid coating material of any suitable character, such as that commonly used for producing speckled, or mottled, surfacings, in the form preferably of relatively large bodies, compared with the bodies produced by an atomizing action hereinafter referred to, with such force that these bodies upon striking the surface to be coated become flattened against the surface, adhering thereto and remaining practically quiescent in their flattened condition preliminary to becoming set, as distinguished from running down the surface against which the bodies of coating fluid are discharged, the several streams of bodies striking the surface to be coated, at substantially the same places thereby to produce a mottled effect of such character as to render it observable from quite a distance, and presenting such characteristics as to present an appearance of depth to the coating, such as is presented in the case of an uncoated mottled material, as for example granite, or the like. It has been heretofore proposed to produce a speckled surface by discharging against the object on which the surface is to be provided, the coating fluid project-

ed against such object by an atomizing action, but such a procedure would fail to produce this desired effect due primarily to the blowing of the coating fluid into finely divided particles by the atomizing action. In accordance with the preferred manner of practicing my invention, as to this phase thereof, I cause the coating fluid to be projected against the object to be coated, to produce the speckled or mottled effect in relatively large bodies, as compared with the relatively fine particles produced by the atomizing action referred to.

My invention, as to another phase thereof, relates to the maintaining of the flow of the coating fluid in accurate predetermined measured quantities, for producing desired coating effects, as distinguished from the varied flow of the several streams in atomizing apparatus.

Referring to the accompanying drawings:—

Figure 1 shows by a longitudinal sectional view, a device which may be employed in practicing my invention. Figure 2 is a plan sectional view of the device of Fig. 1, with certain parts broken away. Figure 3 is a view in end elevation of certain cam devices which may be employed, the shaft carrying them being shown in section, with the section taken at the line 3 on Fig. 4 and viewed in the direction of the arrow. Figure 4 is a section taken at the line 4 on Fig. 1 and viewed in the direction of the arrow; and Figure 5, a view like Fig. 2, of a modification of the structure shown therein.

The particular construction of device illustrated is formed of a casing 10 shown as formed of a casting open at its opposite ends and provided with a diaphragm 11 forming with other parts of the casing 10 a passage 12 for compressed air, this passage containing at one end a pipe section 13 adapted to be connected at its outer end with any suitable supply of gaseous fluid under pressure, as for example compressed air. The passage 12 at its opposite end contains a plurality of restricted outlets 14 shown as extending at an angle to the direction in which the air flows through the main portion of the passage 12. In this construction provision is made for discharging in a plurality of streams, the coating fluids of dif-

2
 ferent colors, or tones, from the device, the pipes through which these streams discharge being represented at 15, and terminating in nozzles, in practice these pipes being adapted for use with nozzles of different sizes as desired. Three of these pipes are shown, these pipes extending crosswise through the passage 12 and through the several outlets 14 for the compressed air, from the walls of which latter the pipes 15 are spaced as shown. The other ends of the pipes 15 connect with the ends of flexible tubes 16, 17 and 18, as for example of common heavy rubber tubing, which lead from suitable sources of the coating fluids of different colors, or tones, to be applied to the surface on which the mottled effect is to be produced.

The sources of the material are not shown, but the material may either flow to the device or be drawn to the latter by the action of the device as desired. Thus it may be provided in receptacles arranged either above the device now being described, in which case the coating material would flow to the device under a head, or on the same level as the outer ends of the tubes 16, 17 and 18, or below such level, and in the two latter instances provision may be made, or not, as desired, for forcing the fluid to the said device. The outer ends of the tubes 16, 17 and 18 extend along the top of the partition 11 which latter thereby forms a support for these tubes in the operation of the mechanism hereinafter described for effecting the discharge of the coating material through these tubes and their outlet pipes 15 in the desired manner. The mechanism just referred to is formed, in the particular construction illustrated, with three presser devices 19, 20 and 21 shown in the form of plates which extend transversely of the tubes 16, 17 and 18 and across the tops thereof. The plate 19 is carried by a pair of levers 22 located within the casing 10 and pivoted each at one end, on a shaft 23 mounted in opposed extensions 24 provided as a part of the casing 10. The plate 20 is connected with a pair of levers 25 likewise pivoted, each at one end, on the shaft 23; and the plate 21 is connected with a pair of levers 26 also each pivoted at one end on the shaft 23, these various sets of levers being independently movable on the shaft 15. The opposite end of the casing 10 is equipped with a housing member 27, within which are located a plurality of rocker-arms 28, shown as six in number to correspond with the number of levers 22, 25 and 26 beneath which they are directly positioned, respectively, as shown, these rocker-arms being pivoted on a shaft 29 secured in the sides of the casing 10, and with their outer extremities connected, through the medium of tension springs 30, with the several levers 22, 25 and 26 directly above them, each of the rocker-arms 28 being provided with a pin

31 extending upwardly through the spring and adapted to co-operate with the under side of the respective one of the levers with which the spring, enclosing it, co-operates. Extending through the spaces between the various levers referred to and the rocker-arms 28, is a shaft 32 journaled at its opposite ends in the sides of the casing 10 and adapted to be driven, as through the worm wheel 33 secured thereon and meshing with a worm 34 on a shaft 35 driven in any suitable manner (not shown). The shaft 32 is provided with a plurality of eccentrics, one of which, represented at 36, extends immediately above the two central rocker-arms 28 connected with the two levers 26, two of which, represented at 37, extend above the rocker-arms 28 to which the respective levers 25 are connected, and two more of which, represented at 38, extend above the two rocker-arms 28 with which the levers 22 are respectively connected, the two eccentrics 37 occupying the same angular position on the shaft and the two eccentrics 38 occupying the same angular position, the eccentric 36 and the two sets of eccentrics 37 and 38 occupying different angular positions about the shaft, in the arrangement shown being positioned about the shaft at an angle of 120° to each other. The described arrangement of the eccentrics is such that in their movement, in the rotation of the shaft 32 in anti-clockwise direction in Fig. 1, they will successively operate the several pairs of rocker-arms 28 which through the described spring connections with the various sets of levers described, cause the presser devices 21, 20 and 19 to close the tubes 16, 17 and 18 at points immediately beneath them in succession, the arrangement being such that at no time are all of the presser devices in a position in which the tubes 16, 17 and 18 immediately beneath them, are open, it being understood that the tubes 16, 17 and 18, by reason of their resiliency expand as the respective presser devices rise relative to these tubes.

Associated with the mechanism described, are means adapted to operate on the tubes 16, 17 and 18 and effect control of the flow of fluid therethrough, auxiliary to the action of the mechanism hereinbefore described and for the purpose hereinafter explained, these means comprising a stationary bar 39 carried by the casing 10 and extending across the tops of the tubes 16, 17 and 18, and presser devices 40, 41 and 42 located immediately beneath the tubes 16, 17 and 18, respectively, and carried on the upper ends of rods 43 which are slidable in webs 44 in the casing 10, the rods 43 having rollers 45 at their lower ends at which they bear against the peripheries of cams 46, 47 and 48 rigidly secured to a shaft 49 journaled in brackets 50 extending from the casing 10, these cams oc-

cuping different angular positions about the shaft 49 preferably 120° apart as represented. The shaft 49 is driven through the medium of a sprocket chain 51 passing over 5 sprockets 52 and 53 on the shafts 49 and 32 respectively.

The operation of the mechanism involving the presser devices 19, 20 and 21 and the operating mechanism therefor, is as follows:

10. Assuming the parts to be in the position shown in the drawings, wherein the presser devices 19 and 20, by reason of the illustrated position of the eccentrics 37 and 38 are in lowermost position in which the tubes 16, 17 and 18 are closed at the portions thereof beneath these presser devices, and the presser device 21 is raised, the continued rotation of the shaft 32 in anti-clockwise direction in Fig. 1 first causes the eccentrics 20 37 to move against the under sides of the levers 25 and in a direction away from the rocker-arms 28 immediately beneath them, thereby lifting these levers to raise the presser foot 20 which permits the tubes 25 16, 17 and 18 to expand at these points. During 30 this movement of the eccentric 37, the eccentric 36 moves into engagement with the rocker-arms 28 immediately beneath it, with the result of causing these rocker-arms and 35 the levers 26 to lower by reason of the spring connections between these rocker-arms and levers, forcing the presser foot 21 against the tubes 16, 17 and 18 with sufficient pressure to close the tubes at these points, these 40 spring connections elongating in this operation, and the arrangement of the parts being preferably as shown by which the levers 26 move downwardly a slight distance only before the levers 25 have reached their uppermost position. Further movement of the 45 shaft 32 in anti-clockwise direction in Fig. 1 operates to move the eccentrics 38 into engagement with the levers 22 immediately above them thereby operating to raise the presser foot 19. In the continued movement 50 of the shaft 28 the eccentrics 37 operate to force the presser foot 20 against the tubes 16, 17 and 18, while the presser foot 21 holds these tubes closed at the portions thereof immediately below it, the presser device 19 55 thereafter moving against the tubes 16, 17 and 18, the presser device 21 moving to the position shown in Fig. 1 after the presser device 20 has closed the tubes beneath the latter. The arrangement of the eccentrics referred to, relative to the presser devices 19, 20 and 21 is such, as shown, that at all 60 times one of the presser devices closes the tubes 16, 17 and 18 and these presser devices are operated in succession from the right to the left in Fig. 1, these successive operations of the presser devices as stated serving to produce a pulsating action on the fluids in the tubes thereby to cause the fluids to be intermittently projected through the outlets

of the pipes 15 where the coating fluids are supplied to the presser devices through the tubes 16, 17 and 18 by pressure produced by gravity flow, or otherwise, the operation of the presser devices 19, 20 and 21 serving to 70 control the discharge of the fluid through the pipes 15 and causing the fluids to discharge from these pipes intermittently, the fluids spurting from the outlets of these pipes intermittently and thereby causing the 75 fluids to issue in separated bodies of relatively large size, depending upon the dimensions of the various parts, as compared with the size of the bodies resulting from the subjection of such fluid to an atomizing action. 80 Where the supply of coating fluids is not supplied to the presser devices 16, 17 and 18 under pressure, as for example where it is located in tanks below these presser devices and does not flow thereto under pressure, the 85 device operates to cause the fluids to flow to the device and forces the fluids out through the pipes 15 as stated. In the case of the use of the device with supplies of coating fluids under conditions requiring the drawing 90 of the coating fluid to these presser devices, as stated, the result above explained is due to the operation of the presser devices 16, 17 and 18 in succession, and in the timed relation as stated, due to the fact that in the 95 operation of these presser devices they are operated in succession from a position in which the tubes 16, 17 and 18 are closed, to a position in which these tubes are open, from the right hand toward the left hand end of 100 the series in Fig. 1, thereby forcing the fluids along the tubes to the left in this figure in such operation producing, by the expanding of these tubes to normal condition, after being contracted, the reduction in fluid 105 pressure at this point which operates to cause the fluids to flow to the left through the tubes 16, 17 and 18. While under some conditions the discharge of the coating fluids from the pipes 15 by the action of the presser 110 devices 16, 17 and 18 alone, may be sufficient to effect the delivery to the surface to be coated, of the coating bodies of the desired size and in the desired flattened condition against the surface, it is preferred that there 115 be associated with the coating fluids discharged through the pipes 15, any suitable gaseous fluid under pressure, as for example, and by preference, compressed air as hereinbefore referred to, which is caused to 120 flow in the direction of movement of the coating fluids discharging from the pipes 15, in enveloping relation to the coating fluids, and preferably at a greater velocity than that at which the coating fluids 125 discharge from the pipes 15, the primary purpose being to present between the bodies of coating fluid and the atmosphere, in the movement of the streams of separated bodies of the coating fluids, from the device 130

1 to the object to be coated, a protecting envelope, whereby the breaking up of these bodies into relatively finely divided condition, by the propulsion thereof against the 5 resistance of the air, as would occur if such shielding means were not provided, is avoided. Where conditions are such that it is desirable, or necessary, that the coating fluids as they issue from the pipes 15, as stated, be 10 subjected to an accelerating action, the fluid pressure discharged through the openings 14 may be under such pressure that it will operate on the separated bodies of coating fluid to accelerate their movement toward the object to which they are to be applied, this accelerating action being in the nature of a boosting action. In accordance with the preferred manner of practicing my invention such boosting fluid pressure is applied adjacent 15 the outlets of the pipes 15 and such use thereof as to break up the separated bodies of coating fluid, as they issue from the pipes 15, into such small bodies as are produced when a stream of fluid is subjected to an 20 atomizing action, is to be avoided. However, in so far as a certain phase of my invention is concerned, it is within my invention to provide such a pressure and flow of fluid-pressure that the bodies of coating fluid delivered 25 with each pulsating action of the device, through the outlets 15, are reduced to finely divided condition resembling those produced by an atomizing action, the device in so operating presenting an advantage over 30 the use of an atomizing action alone, in that the fluid is propelled through the outlets by a force which alone would cause the fluid to be spurted from the device toward the object against which it is to be applied.

35 40 Furthermore, as regards the feature of producing and maintaining accurate measured flow of the coating fluids as is possible in the arrangement disclosed, this feature may be used, within my invention, regardless 45 of the manner of effecting the delivery of the bodies of coating fluid to the object to be coated, and regardless of the variation in the regularity of, yet measured, flow hereinafter referred to.

50 55 As will be understood from the drawings, the outlets of the pipes 15 are grouped relatively closely together, this being the preferable arrangement, whereby the streams of separated bodies of the coating fluids strike 60 the object to be coated and against which they will discharge (preferably by the operator holding the device by grasping it at the casing thereof) at closely adjacent portions of such surface, some of the bodies of coating fluids becoming commingled with others of such bodies which produces a cluster-effect at different points on the surface, the appearance produced being that of a mottled surface of considerable depth.

65 70 It will be understood that surfacing ef-

fects of widely differing character may be produced, as for example by varying the dimensions of the parts of the device, and the fluid-pressure employed, which causes the sizes of the bodies of coating fluid delivered to the object to vary. Furthermore widely different surfacing effects may be produced by the employment of mechanism, auxiliary to the presser-devices herein first described, as for example that formed of the 75 presser devices 40, 41 and 42, the operation of which in the particular arrangement shown causes the several streams of bodies to irregularly discharge, but by a measured flow, from the device. The mechanism just referred to as shown is merely illustrative of means for producing variation in the control of the streams, it being readily understood that by omitting certain of the cams on the shaft 49, or varying their shape, or the timed operation thereof, relative to each other, as shown, a great variety of surfacing effects may be produced.

In Fig. 5 I have shown by way of illustration an arrangement of parts whereby a variation in the discharge of fluids from a plurality of conduits may be accomplished in a different manner than shown in the preceding figures. In this particular arrangement two flexible conduits, like the conduits 16, 17 and 18 are provided, these conduits being represented at 54 and 55, with their discharge pipes 56 and 57 like the pipes 15, projecting through openings 58 and corresponding with the openings 14. In this construction four presser devices, 59, 60, 61 and 62 are provided, the presser device 59 co-operating with the pipe 54 only, the presser device 62 with the pipe 55 only and the presser devices 60 and 61 located between 95 the presser devices 59 and 62 co-operating with both of the tubes 54 and 55 to operate to collapse these tubes as explained of the presser devices of the preceding figures. The presser device 59 is carried on a plurality of levers 63, the presser device 62 is carried on a plurality of levers 64, the presser device 60 on a plurality of levers 65 and the presser device 61 on a plurality of levers 66, these levers being pivoted on 100 a shaft 67 secured in the casing 10. These various levers extend to the left in Fig. 5 (these levers being shown broken away in this figure as they are in Fig. 2) over eccentrics mounted on a shaft 68 and corresponding with the shaft 32 and driven through the medium of a worm-wheel 69 operated by a worm 70 on the shaft 71 driven in any suitable manner. The eccentrics are indicated at 72, 73, 74, 75 and 76, the eccentrics 72 and 76 occupying the same angular position about the shaft 68, and the eccentrics 73, 74 and 75 occupying different angular positions about the shaft, preferably 90° apart, the eccentric 73 extend- 115 120 125 130

ing upwardly and the eccentric 74 extending downwardly. The eccentrics 72 to 76 co-operate with the various levers described to operate the latter by the same kind of an action as explained of the eccentrics in the preceding figures, the eccentrics 72 and 76 extending beneath the levers 65, the eccentric 73 beneath the levers 63, the eccentric 74 beneath the levers 66 and the eccentric 75 beneath the levers 64. Extending below the eccentrics referred to are a series of rocker-arms pivotally supported on a shaft 77 corresponding with the shaft 29, these rocker-arms corresponding with the arms 68 and being provided as follows: One of these rocker-arms represented at 78 extends beneath the eccentric 72, another rocker-arm 79 extends below the eccentric 76, a pair of these rocker-arms represented at 80 extend beneath the eccentric 73, another pair of these rocker-arms represented at 81 extend beneath the eccentric 74 and another pair of these rocker-arms represented at 82 extend beneath the eccentric 75, the outer ends of these rocker arms connecting, by means of coil spring devices 83 like the springs 31, with the levers immediately above them as in the case of the structure of the preceding figures. Thus the rocker-arms 78 and 79 are connected with the two levers 65 respectively; the rocker-arms 80 are connected with the levers 63 respectively; the rocker-arms 81 are connected with the levers 66, respectively; and the rocker-arms 82 are connected with the levers 64, respectively.

In the rotation of the shaft 68, as will be readily understood, the presser devices are operated in succession from the right hand 46 toward the left hand side of Fig. 5, to effect the projection of the fluids through the outlets 57 by an intermittent action, in the same manner as explained of the construction of the preceding figures, except that by arranging the presser devices as shown, the projection of the fluids through the conduits 54 and 55 occurs alternately instead of the projection from these tubes occurring simultaneously, whereby the bodies of coating fluids discharged against the object on which the surfacing is to be applied, from the conduit 54 do not strike the object at the same time that the bodies discharged from the conduit 55, whereby a different effect is produced than in the case where they are discharged simultaneously. It will be understood that such means for producing variation in discharge may, if desired, be used in connection with an auxiliary control 50 mechanism such for example as that shown in the preceding figures and comprising the presser devices 40, 41 and 42.

While I have illustrated and described certain ways of carrying out my invention 65 and have illustrated and described a partic-

ular construction suitable for practicing it, I do not wish to be understood as intending to limit the invention thereto, as my improved method may be practiced in other ways than the specific way described and by the use of other apparatus.

By way of further example of the practicing of my invention, by other structures than those illustrated it may be stated that under some conditions of use, where the fluids are supplied to the flexible conduits under pressure, less than the number of presser devices shown, may be employed, even to the extent of employing only one which would operate to alternately open and close the conduits to the flow of fluids therethrough thereby producing an intermittent discharge of the fluids through the conduits.

What I claim as new and desire to secure by Letters Patent is:

1. In the art of coating surfaces, the method which consists in discharging against the object to which the coating is to be applied, a plurality of streams of separated bodies of coating fluid directed against said object and maintaining a predetermined measured flow of such bodies to said object.

2. In the art of coating surfaces, the method which consists in discharging against the object to which the coating is to be applied, a plurality of streams of separated bodies of coating fluid of relatively large size compared with those produced by an atomizing action.

3. In the art of coating surfaces, the method which consists in discharging against the object to which the coating is to be applied, a plurality of streams of separated bodies of coating fluid of relatively large size compared with those produced by an atomizing action and maintaining a predetermined measured flow of such bodies to said object.

4. In the art of coating surfaces, the method which consists in discharging against the object to which the coating is to be applied, a plurality of streams, having a predetermined relation, of separated bodies of coating fluid of relatively large size compared with those produced by an atomizing action.

5. In the art of coating surfaces, the method which consists in discharging against the object to which the coating is to be applied, a plurality of streams, by a predetermined timing, of separated bodies of coating fluid of relatively large size compared with those produced by an atomizing action.

6. In the art of coating surfaces, the method which consists in discharging against the object to which the coating is to be applied, a plurality of streams of separated bodies of coating fluid of relatively large size compared with those produced by

an atomizing action, and varying the timing of the streams relative to each other to produce different effects.

7. In the art of coating surfaces, the method which consists in discharging against the object to which the coating is to be applied, a plurality of streams of separated bodies of coating fluid of relatively large size compared with those produced by an atomizing action, and varying the timing and volume of the streams relative to each other to produce different effects.

8. In the art of coating surfaces, the method which consists in causing coating fluids to be projected intermittently through the outlet ends of conduits to cause discharge of the fluid from each thereof in separated bodies of a cross-sectional area substantially equal to the cross-sectional area of the outlets respectively, and delivering the coating fluid against the object to which it is to be applied with sufficient force to cause it to flatten against the object.

9. In the art of coating surfaces, the method which consists in causing fluids to be projected intermittently through the outlet ends of a plurality of conduits, respectively, to cause discharge of the fluid from each thereof in separated bodies and causing said bodies to become separated into smaller bodies.

10. In the art of coating surfaces, the method which consists in causing fluids to be projected intermittently through the outlet ends of a plurality of conduits, respectively, to cause discharge of the fluid from each thereof in separated bodies and blowing said bodies into separated condition by subjecting the bodies to gaseous fluid under pressure directed against said bodies substantially in the direction of movement of said bodies.

11. In the art of coating surfaces, the method which consists in causing coating fluids to be projected in the form of streams of connected particles, intermittently through the outlet ends of a plurality of conduits, respectively, to cause discharge of the fluids from each thereof in separated bodies and causing said bodies to become separated into smaller bodies.

12. In the art of coating surfaces, the method which consists in causing coating fluids to be projected in the form of streams of connected particles, intermittently through the outlet ends of a plurality of conduits, respectively, to cause discharge of the fluids from each thereof in separated bodies and blowing said bodies into separated condition by subjecting the bodies to gaseous fluid under pressure directed against said bodies substantially in the direction of movement of said bodies.

13. In the art of coating surfaces, the method which consists in causing coating

fluids to be projected intermittently along conduits, respectively, through which the fluids discharge against the object to be coated, and causing said bodies to become separated into smaller bodies.

14. In the art of coating surfaces, the method which consists in causing coating fluids to be projected intermittently along conduits, respectively, through which the fluids discharge against the object to be coated, and subjecting the fluids when they are projected to certain points to gaseous fluid under pressure for blowing successive portions of the fluids into separated bodies.

15. In the art of coating surfaces, the method which consists in causing coating fluids to flow intermittently along conduits, respectively, through which the fluids discharge against the objects to be coated, and causing portions of the fluid to become separated into smaller bodies.

16. In the art of coating surfaces, the method which consists in discharging against the object to which the coating is to be applied, a plurality of streams of separated bodies of coating fluid, and varying the timing of the streams relative to each other to produce different effects.

17. In the art of coating surfaces, the method which consists in discharging against the object to which the coating is to be applied, a plurality of streams of separated bodies of coating fluid, and varying the timing and volume of the streams relative to each other to produce different effects.

18. In the art of coating surfaces, the method which consists in discharging through a plurality of conduits by force within said conduits and against the object to which the coating is to be applied, a plurality of streams of separated bodies of coating fluid directed against said object and maintaining a predetermined measured flow of such bodies to said object.

19. In the art of coating surfaces, the method which consists in discharging against the object to which the coating is to be applied, to strike the object within substantially the same area, a plurality of streams of separated bodies of coating fluid directed against said object and maintaining a predetermined measured flow of such bodies to said object.

20. In the art of coating surfaces, the method which consists in discharging against the object to which the coating is to be applied, to strike the object within substantially the same area, a plurality of streams of separated bodies of coating fluid of relatively large size compared with those produced by an atomizing action.

21. In the art of coating surfaces, the method which consists in causing coating fluids to be projected intermittently

- through the outlet ends of conduits to cause discharge of the fluid from each thereof in separated bodies of a cross-sectional area substantially equal to the cross-sectional area of the outlets, respectively, and delivering the coating fluid against the object to which it is to be applied to strike the object within substantially the same area and with sufficient force to cause it to flatten against the object.
22. In the art of coating surfaces, the method which consists in causing fluids to be projected intermittently through the outlet ends of a plurality of conduits, respectively, to cause discharge of the fluid from each thereof in separated bodies and causing said bodies to become separated into smaller bodies and strike the object to be coated within substantially the same area.
23. In the art of coating surfaces, the method which consists in causing coating fluids to be projected intermittently along the conduits, respectively, through which the fluids discharge against the object to be coated, and causing said bodies to become separated into smaller bodies and strike the object to be coated within substantially the same area.

MAJOR E. GATES.
